UNITED STATES PATENT OFFICE.

GEORGE H. DAY, OF SOUTHRIDGE, MASSACHUSETTS, ASSIGNOR TO AMERICAN OPTICAL COMPANY, OF SOUTHRIDGE, MASSACHUSETTS.

OPHTHALMIC MOUNTING.

1,159,751.

Specification of Letters Patent.

Patented Nov. 9, 1915.

Application filed March 22, 1915. Serial No. 16,062.

To all whom it may concern:

Be it known that I, GEORGE H. DAY, a citizen of the United States, residing at Southbridge, in the county of Worcester and 5 State of Massachusetts, have invented certain new and useful Improvements in Ophthalmic Mountings, of which the following is a specification.

My invention relates to improvements in 10 ophthalmic mountings, and has particular reference to an improved type of mounting which may be readily collapsed to facilitate carrying of same.

A further object of my invention is the 15 provision of an improved type of ophthalmic mounting particularly adapted for use in protection of the eye, as well as in the retention of correction lenses therebefore, which has the parts so constructed and arranged as 20 to be capable of ready folding into minimum space while providing a rigid and durable construction when open.

Further objects of my invention include 25 the simplification of the several parts and an improvement in the various details of the construction to at one time increase the efficiency of the device while lessening the cost of manufacture of the same, and it will be understood that I may make any modifications 30 in the specific details of construction shown and described within the scope of the appended claims without departing from or exceeding the spirit of my invention.

Figure I represents a front view of my 35 improved mounting with the parts in open position. Fig. II represents a top plan view thereof. Fig. III represents a plan view of the lens retaining parts in separated relation with other parts removed. Fig. IV represents a sectional view on the line IV—IV of Fig. I. Fig. V represents a plan view of the shield member before attachment to the lens frames. Fig. VI represents a plan view of the blank for the attaching portion of the 45 shield member. Fig. VII represents a view of a modified blank adapted to carry the temple. Fig. VII represents a plan view of a construction with parts in folded position. Fig. IX represents a side elevation 50 with the parts in the position shown in Fig. VIII. Fig. X represents a detail view of a modified construction of attaching member. Fig. XI represents a similar view. Fig. XII represents another modification of at-

taching member. Fig. XIII represents still 55 another modification of attaching member. Fig. XIV represents a fragmentary view illustrating a modified temple attachment, and Fig. XV represents a view with the parts in folded position.

Referring to the drawings, wherein is illustrated the preferred embodiment of the invention, the numeral 1 designates the lenses which are maintained in the usual frame members 2 and 3. These frame members may be made from metal or from a suitable composition such as zylonite, and each of these frame members at its inner edge is provided with an inwardly extending lug or handle portion 4 terminating in an abutment shoulder 5, the two portions 4 being provided with interlocking ears or the like 6 connected by a pintle 7, to facilitate ready folding of the bridge or lens connecting member formed by the two portions 4.

As previously mentioned, the particular construction illustrated is adapted for use as an eye protecting member. It is to be understood, however, that the various features of construction herein described are adapted for use with any ophthalmic mounting and not merely for use in connection with a protective style of mounting.

In connection with Fig. I particular attention is invited to the position occupied by the temples 8, the ears or brackets 9 to which the same are pivoted being disposed at upwardly converging angles relative to the axial line of the frame. On account of 90 this arrangement the temples in place of folding substantially across the lenses with the ear hook portions thereof depending below the mounting, necessitating distortion of the temples in placing the mounting 95 within its ordinary case, lie in such position that the ear hooks follow substantially the curvature of the eye wires or frame, while the sides of the temples extend diagonally from the point of attachment to the top of 100 the opposite eye wire or frame, the temples when closed thus lying substantially within the marginal limit of the mounting and enabling the same to be put within a very 105 small case without any bending or distortion of the temples.

To exclude entrance of dirt or other foreign substances at the sides of my mounting,

I have provided an improved shield or protecting member 10, which may be formed of fabric, leather, rubber or other pliable material shaped to suitable form and having its 5 lower edge fitting within the rim 11.

The blank for one form of rim is illustrated in Fig. VI and another form in Fig. VII. In that form illustrated in Fig. VI, the rim 11 comprises a straight band portion 10 having at one edge a plurality of ears 12 adapted to be doubled back to clampingly engage and secure the edge of the shield between the body portion 11 and said ears 12. At the same time the rim is provided with 15 the additional depending members 13 furcated at their outer portions to provide the prongs or points 14, the formation of the furcations preferably being such as to provide an enlarged circular or similarly shaped 20 recess 15. The purpose of this recess 15 should be readily apparent by reference to Fig. IV, from which it will be seen that in the case of a composition frame of any nature the same may be suitably softened and 25 the members 13 forced downward thereinto by pressure, the prongs biting into and readily piercing or pressing aside the material, while the shaping or retaining of the frame in position exteriorly during the operation of forcing the members 13 downward 30 thereinto tends to cause the material so far as possible to resist outward forcing under action of the prongs and consequently the material will entirely fill in the recess 15 coming behind the shoulder portion 16 of 35 the prongs, and when cooled or hardened securely locking the prongs in position, it being necessary if desired to withdraw the prongs to apply sufficient force so that the 40 prongs will cut through the portion 17 of material filling the recess or aperture 15. In this connection attention is also invited to Figs. X and XI, in which slightly modified forms of members 13 are illustrated. 45 These forms have been particularly illustrated with pivot ears 9 for receiving temples or the like, but it is to be understood that they are alternative forms for the construction shown in Fig. VI, which may be 50 substituted therefor.

In Fig. X, I have shown the prongs 14 as provided with the pair of shoulders 16, making a pronounced barb, while in Fig. XI, I have shown two of the barbs 14 as employed 55 together, thus gaining a retaining action on the outer as well as the inner edges of the members 14 shown in Fig. V.

While in Fig. V the shield is shown with two rims 11 for retaining it in position, in 60 Fig. VII, I have shown a blank adapted to form a single continuous rim, this blank being provided with a pair of ears 9 carried by a neck 18, whereby the ears may be bent inward to lie at the desired angle to insure 65 correct folding of the temple, the neck being

slightly twisted if desired to facilitate exact positioning of the united ears and the outer portion of the neck serving as an abutment to engage the end of the temple and limit the opening movement thereof.

In Fig. XII, I have illustrated a slightly modified construction for use in pivotally attaching a temple to a frame, in this form there being provided a conical point 19 with a cylindrical neck 20 terminating in the pivot ear or ears 9. This member is forced into the material of the frame in the same manner as the member 13 previously referred to, the peripheral shoulder 16 at the base of the cone preventing accidental withdrawal thereof, while the conical and cylindrical shape of the parts permit of ready rotation. A modification of this idea is illustrated in Fig. XIII, in which I have employed a hollow wedge shaped member formed from a flat blank and with the cylindrical member 20 swiveled in one side of the wedge, whereby the wedge is pressed into and firmly retained within the rim or frame 2 by the flow of the material of the frame, while the portion 20 is freely rotatable to permit of movement of the temple as desired. These forms may be employed when it is preferred to have a temple which may either fold directly along the axis of the mounting or may be swung around at will in the folding of the mounting. This last described construction is particularly advantageous in those instances when it is desired to fold the protector into the smallest possible compass. In this construction, as is indicated in Figs. VIII and IX the two portions 2 and 3 are swung on the pintle 7 into folded relation and the temples are also closed carrying downward with them 105 the flexible shield members 10.

For the most complete folding it is essential that the temples be of readily flexible material. With temples of this character it is then possible to swing the temples on their pivotal connection and at the same time coil the same, as indicated in Fig. IX, so that the coil is substantially circular or spiral in form and lies within the edge limits of the frame members 2 and 3. It 110 will thus be seen that although this is a spectacle type of mounting, that is, one retained by temples or the like, the entire space required to receive the same is but slightly greater than the diameter of the lenses contained in the mounting, while at the same time excessive distortion of any of the parts is avoided and their folding is accomplished in an exceedingly simple and satisfactory manner. It will thus be noted that when in 115 folded form the mounting may be readily slipped into a dress or watch pocket, and has no disagreeable bulk. It will further be noted that several of these mountings may be placed in the space ordinarily occupied by a 120

single protector, particularly recommending its use, therefore, to autoists or others desiring to carry an additional supply of mountings in case of breakage, or when persons unequipped with protectors become members of the party.

In Figs. XIV and XV, I have illustrated another modification of my invention in which the flexible shield member is secured 10 to the frame through the medium of the member 11 and parts as hitherto described. In this form of the invention, however, in place of the temple being directly secured to the frame the same is carried by the temple 15 minus of the flexible shield member being either rigidly or loosely connected thereto as may be preferred. The advantage of this type of construction should be readily apparent by reference to Fig. XV, from which 20 it will be seen that when the parts are folded the flexible shield member may be readily crumpled or doubled upon itself to bring one terminus of the short temple immediately adjacent the frame and extending 25 in any desired direction relative thereto, while the hook curves toward the central or bridge portion of the frame forming an extremely compact readily folded or carried construction.

30 I claim:

1. In an ophthalmic mounting embodying a non-metallic frame member, a fitting therefor, comprising a body portion having a furcated member projecting therefrom, said 35 furcations inclosing a space therebetween and having shoulders adjacent their termini forming a partial closure for the space, whereby when the furcations are pressed into the frame the material of the frame will 40 fill the space therebetween and lock behind the shoulders to prevent accidental withdrawal of the parts therefrom.
2. In an ophthalmic mounting, the combination with a lens receiving frame, of a 45 shield attaching frame carried thereby, said shield attaching frame comprising a rim having a plurality of ears formed at one edge thereof, certain of said ears being reversely bent to clampingly secure the shield 50 between the rim and ears and the other ears extending substantially in line with the

rim and being secured to the lens receiving frame, substantially as described.

3. The combination with a composition frame, of a fitting therefor having a substantially sharp entrance portion, a shoulder adjacent the entrance portion, and a reduced portion extending outwardly beyond the shoulder, whereby the material of the frame may be forced behind the shoulder to securely lock the entrance portion therewithin, and a fitting carried by the reduced portion exterior to the frame. 55

4. In an ophthalmic mounting, the combination with a composition frame, of a shield 60 therefor, and a connection between the shield and the frame, said connection comprising means for gripping the shield and anchors for embedment in the frame. 65

5. An ophthalmic mounting comprising a lens frame, a shield therefor, and means embedded in the frame for securing the shield thereto. 70

6. A mounting of the character described, comprising a lens frame, a shield therefor, 75 and means secured to the shield and having portions thereof embedded in the frame to secure the shield to the frame.

7. In an eye protector, the combination with a rigid lens engaging portion and a flexible shield, of a connecting device for 80 said portions comprising a metallic strip having ears bent to clampingly engage one of said members and having hook-like projections piercing and engaging the other of 85 said members to securely connect the parts.

8. An ophthalmic mounting, including a lens engaging frame, a shield, and a channel member for connecting said parts having portions of the channel squeezed to clampingly engage one of the parts and having other portions of the channel formed into projecting hook-like ears, said ears piercing 90 the other member and the hook engaging with said other member to securely connect 95 the parts.

In testimony whereof I affix my signature in presence of two witnesses.

GEORGE H. DAY.
